CLAIM

We claim the ornamental design for a drain cover, as shown and described.

DESCRIPTION

FIG. 1 is a top perspective view of a first embodiment of a drain cover of the present invention;
FIG. 2 is a top view thereof;
FIG. 3 is a bottom view thereof; and
FIG. 4 is a first side view thereof, wherein the second, third, and fourth side views are mirror images thereof;
FIG. 5 is a top perspective view of a second embodiment of a drain cover of the present invention;
FIG. 6 is a top view thereof;
FIG. 7 is a bottom view thereof; and
FIG. 8 is a first side view thereof, wherein the second, third, and fourth side views are mirror images thereof
FIG. 9 is a top perspective view of a third embodiment of a drain cover of the present invention;
FIG. 10 is a top view thereof;
FIG. 11 is a bottom view thereof; and,
FIG. 12 is a first side view thereof, wherein the second, third, and fourth side views are mirror images thereof.
The broken lines and unshaded planes depict portions of the drain cover that form no part of the claim.
